UNITED STATES PATENT OFFICE.

JASPER E. GOODWILL, OF OMAHA, NEBRASKA.

HOISTING APPARATUS FOR SCAFFOLDS.

1,231,014.

Specification of Letters Patent. Patented June 26, 1917.

Application filed January 20, 1917. Serial No. 143,458.

To all whom it may concern:

Be it known that I, JASPER E. GOODWILL, a citizen of the United States, residing at Omaha, in the county of Douglas and State 5 of Nebraska, have invented certain new and useful Improvements in a Hoisting Apparatus for Scaffolds, of which the following is a specification.

The invention relates to a hoisting apparatus for scaffolds, and has for its object, broadly, to provide apparatuses by means of which heavily loaded scaffolds may be readily elevated or lowered, the parts to be few and simple so that they may be manufactured economically, will be efficient in 10 operation, and durable and convenient in use.

The invention consists of the novel construction, combination and arrangement of 20 parts as described herein and claimed and as illustrated in the accompanying drawing, wherein,

Figure 1 is a view in side elevation of the apparatus and Fig. 2 is a view of the 25 same in longitudinal section, parts of the upper gripping member being disposed in engagement with the cable, and the parts of the lower gripping member being shown in disengaged relation with the cable. Fig. 3 is a view of the apparatus in longitudinal section taken at right angles to the view shown in Fig. 2, as on line 3 3 of Fig. 2. Fig. 4 is a plan view of one of the operating or hand levers.

Referring now to the drawing for a more particular description, numeral 5 indicates a lower gripping member, and at 6 is indicated an upper gripping member, each being adapted, normally, to engage or grip 30 the elongated, upright support 7 by action of the opposed springs 8, and adapted to be released from said support by manually pressing upwardly upon a hand-lever 9.

While the elongated support 7 is shown 45 as a cable, it will be understood that operation of the apparatus would be substantially the same if elongated bars, strap-iron, pipe or strands were employed, these supports being of any required length to reach to the 50 top of a wall or building, if necessary, their upper ends in all instances being secured at some distance above the scaffold 10 which carries the load.

Calling attention to the gripping member 5, 6, said members 5 and 6 being identically the same in construction, numerals 11 indi-

cate a pair of opposed, rectangular plates, and between their lower ends is disposed, to project outwardly thereof, a pair of opposed arms 12, preferably secured thereto 60 by bolts 13.

At 14 and 14' are indicated a pair of opposed, toothed lever-sectors, each being mounted eccentrically and adapted to swing upon a bolt 15 traversing the plates 11, and 65 by action of the springs 8, connected with the arms 12, these sectors will normally grip the support or cable 7, as a holding means for supporting the weight of the scaffold.

Numerals 16 and 16' indicate a second pair of opposed, toothed lever-sectors eccentrically mounted upon the plates 11 by bolts 17 carried by the plates 11, and it will be understood that stresses directed downwardly of the scaffold will automatically cause the toothed or milled sectors to engage or grip the cable as means, additional to the first named sectors, for supporting 70 said scaffold.

I employ a plurality of vertical links, these being arranged in pairs, as the pairs 18 and 19, the pair of links 18 having a pivotal connection by means of bolts 20 with and between the ends of the lever-sectors 14', and the pair of links 19 having a similar connection 21 with the lever-sectors 14. The lower ends of the links mentioned are pivotally connected with a pair 75 of cross-bars 22.

The hand-lever 9 is pivotally mounted at its inner end upon the plates 11 as indicated at 23, and is fulcrumed at 24 upon a coupling bar 25, the latter having a pivotal connection, as indicated at 26 upon the outer end of the lever-sector 16'. At 9' is indicated a lever having its inner end pivotally connected with the plates 11, as indicated at 23', its outer end having a pivotal connection 24' with a coupling bar 25', the latter being pivotally connected, as indicated at 26' with the outer end of a lever-sector 16. Numerals 27 indicate bolts for securing the plates 11 together and in spaced relation. In this connection it should be stated that levers 9, 9' and the operating lever 32, in form, are substantially as shown in Fig. 4, the arms x being suitably spaced apart for engaging the parts with which they are connected.

Since the parts thus described for the gripping-member 6 are identical in construc-

tion and arrangement with the parts of the gripping-member 5, it is not considered necessary to particularly describe the construction of the gripping-member 5. While I have shown bolts for the pivotal connections, I do not wish to be understood as limiting myself in this respect, but bolts are preferred since the parts of each gripping-member may be conveniently assembled, and if required, 10 they may be readily disconnected.

In order that the gripping-members 5 and 6 may be connected and may be operated in a manner to elevate or to lower the scaffold the lower member, 5 is provided with the 15 pair of side-bars 28, their lower ends being secured to the scaffold by any suitable means, the means herein shown being the bolt 29 traversing the spacing member or sleeve 30, said side-bars projecting somewhat above the 20 plates 11 to provide a pivotal mounting 31 for the operating-lever 32, the cross-bars 22 of member 6 being provided with the pair of links or actuating-arms 33 having pivotal connections 34 with said cross-bars.

25 Numerals 35 indicate the pivotal mountings for the lever-sectors 16' and 16 upon the respective pairs of links 18 and 19. Numerals 36 indicate the pivotal mountings of the last named links upon the cross-bar 22. 30 Numerals 37 indicate the pivotal mounting of the operating lever 32 upon the links 33. At 38 (Figs. 1, 3,) is indicated the pivotal connection for the inner ends of the hand-lever 9 and 9'. Straps 39 are employed as 35 additional holding means for links 28, said straps being disposed on the outer sides of said links, near their upper ends and connected with the plates 11 of member 5.

From the description it will be understood 40 that if the free end of either of the hand levers 9 are swung upwardly a limited distance, the links 18 and 19 will have corresponding movements, and since the sectors are mounted eccentrically, all of them will be 45 released from the cable, the levers 9' being actuated coincidentally with levers 9 on account of their pivotal connections 38, and it will be noted that no manual operation is required for causing engagement of the sectors 50 with the cable since the opposed springs 8 cause the milled parts of the sectors to make this engagement; and it is obvious that any increase in the weight of the scaffold will cause an increased degree of pressure of the 55 sectors against the cable to prevent any movement of the members 5 and 6 longitudinally thereof.

In operation, the scaffold may be readily and conveniently elevated by use of the apparatus. To accomplish this, the sectors of the lower gripping-member 5 are first disposed as shown in Fig. 2 for the upper gripping-member 6, so that the sectors of said member 5 will engage the cable 7, the weight 65 of the scaffold thereby being sustained by the

member 5. The operator then swings the lever 9 of member 6 upwardly a limited distance, against the resistance of springs 8, so that the sectors of said member 6 will be released from the cable, and also causes an 70 upward swinging movement of the operating lever 32 to elevate member 6, which, upon releasing the hand lever 9 of said upper member 6, will permit the sectors of said upper member 6 to immediately engage the 75 cable. The operator then causes an upward swinging movement of the hand lever 9 of member 5 for releasing the sectors of said member from the cable, and by imparting a downward swinging movement to the hand 80 lever 32, said member 5 will, together with the scaffold, be elevated; and the operation may be repeated for elevating the scaffold any required distance longitudinally of the 85 cable.

To lower the scaffold the operation is the reverse to that just described; that is to say, the upper member 6, by use of its lever 9 and the lever 32, is lowered, after which the scaffold is lowered by use of the lever 9 of the lower member 5, the lever 32 being permitted to swing gradually upward, the scaffold thereupon moving downwardly free from shocks or undue vibration, this last operation being repeated until the scaffold 95 has been lowered a required distance longitudinally of the cable.

By the construction as described, if it is desired to increase the distance to which the scaffold may be shifted at each operation, it 100 is obvious that this may be accomplished by increasing the distance between the pivotal mountings 31 and 37, and in constructing the apparatuses, this distance may be conveniently adjusted by use of apertures 40 formed in the lever 32 for the insertion of the pivot 37, depending upon the size or weight of the scaffold and amount of material to be supported or hoisted.

While I have shown and described two 110 opposed plates 11, and prefer the use of two, the apparatus would be operative if a single plate was employed and therefore I do not wish to limit myself in this respect, and it is understood that size, form and proportion, and minor details of construction 115 may be changed, if desired, since I have illustrated only one embodiment of the invention, the scope of said invention being determined by the appended claims.

I claim:

1. In a scaffold hoisting apparatus, the combination with an upright elongated support, of an upper gripping member, and a lower gripping member, each gripping member consisting of a pair of connected plates upon opposed sides of the support, a pair of opposed arms projecting outwardly of and connected with said plates, a pair of opposed, toothed lever-sectors between and 125

eccentrically mounted on said plates, springs connecting the arms and said lever-sectors for causing normal engagement of the latter with the support to prevent a movement 5 of the gripping-members longitudinally of said support, a second pair of opposed, toothed lever-sectors between and eccentrically mounted on said plates, links arranged in pairs outwardly of said plates and pivotally 10 connected with said lever-sectors, means for moving the links against the action of the springs for releasing the lever-sectors from said support, and means for moving one of said gripping members longitudinally of the support after its lever-sectors have been released.

2. In a scaffold hoisting apparatus, the combination with an upright, elongated support, of an upper gripping-member, and a 20 lower gripping-member, each gripping-member being provided with a plate, a pair of opposed toothed lever-sectors eccentrically mounted on said plate, resilient means for causing normal engagement of the lever-sectors with the support to prevent a movement 25 of the gripping-members longitudinally thereof, a second pair of opposed, toothed lever-sectors eccentrically mounted on said plate, links pivotally connected with said lever-sectors, means for moving the links against the action of said resilient means for releasing the lever-sectors from said support, and means for moving one of said gripping-members longitudinally of the 35 support after its lever-sectors have been released.

3. In a scaffold hoisting apparatus, the combination with an upright, elongated support, of an upper gripping-member, and a 40 lower gripping-member, each gripping-member being provided with a plate, a pair of opposed arms projecting outwardly of and rigidly connected with said plate, a pair of opposed, toothed lever-sectors eccentrically mounted on said plate, springs connecting the arms and said lever-sectors for causing normal engagement of said lever-sectors with the support to prevent a movement of the gripping-members longitudinally of said 45 support, a second pair of opposed, toothed lever-sectors eccentrically mounted on said plate, links pivotally connected with said lever-sectors, means for moving the links against the action of the springs for releasing the lever-sectors from said support, and means for moving one of said gripping-members longitudinally of the support after its lever-sectors have been released.

4. In a scaffold hoisting apparatus, the 50 combination with an upright, elongated support, of an upper gripping-member, and a lower gripping-member, each gripping-member consisting of a pair of connected plates upon opposed sides of the support, a pair 55 of opposed lever-sectors between and ec-

centrically mounted on said plates, resilient means for causing normal engagement of the lever-sectors with the support to prevent a movement of the gripping-members longitudinally thereof, a second pair of opposed lever-sectors between and eccentrically mounted on said plates, links arranged in pairs outwardly of said plates and pivotally connected with said lever-sectors, means for moving the links against the action of the 70 springs for releasing the lever-sectors from said support, and means for moving one of said gripping-members longitudinally of the support after its lever-sectors have been released. 75

5. In a scaffold hoisting apparatus, the combination with a suspended cable, of a gripping-member, and a second gripping-member, each consisting of a pair of connected plates upon opposed sides of the cable, a pair of opposed arms projecting outwardly of and connected with said plates, a pair of opposed lever-sectors between and eccentrically mounted on said plates, springs connecting the arms and said lever-sectors 80 for causing normal engagement of the lever-sectors with the cable to prevent a movement of the gripping-members longitudinally of said cable, a second pair of opposed lever-sectors between and eccentrically mounted on said plates, links arranged in pairs, each pair of links being provided with a cross-bar and having pivotal connections with said lever sectors, means for moving the links against the action of the 85 springs for releasing the lever-sectors from said cable, a pair of actuating-arms pivotally connected with the cross-bars of the second gripping-member, and an operating-lever having pivotal connections with the first 90 gripping-member and the actuating-arms of the links of the second gripping-member for moving one of said gripping-members longitudinally of the cable after its lever-sectors have been released. 95

6. In a scaffold hoisting apparatus, the combination with a suspended cable of a gripping-member, and a second gripping-member, each including a plate, a pair of opposed lever-sectors eccentrically mounted 100 on the plate, resilient means for causing normal engagement of the lever-sectors with the cable to prevent a movement of the gripping-members longitudinally thereof, a second pair of opposed lever-sectors eccentrically mounted on said plate, links connected at one of their ends and having pivotal connections with said lever-sectors, means for moving the links against the action of the resilient means for releasing the 105 lever-sectors from the cable, a pair of actuating arms having pivotal connections with the connected links of the second gripping-member, and an operating-lever having 110 pivotal connections with the first gripping-member. 115

7. In a scaffold hoisting apparatus, the combination with an upright, elongated support, of an upper gripping-member, and a lower gripping-member, each gripping-member consisting of a pair of connected plates upon opposed sides of the support, a pair 120 of opposed lever-sectors between and ec-

ping-member for moving one of said gripping-members longitudinally of the cable after the lever-sectors thereof have been released.

5 7. In a scaffold hoisting apparatus, the combination with a supporting cable, of a gripping-member, and a second gripping-member, each gripping-member including a pair of connected plates, a pair of opposed lever-sectors between and eccentrically mounted on the plates, resilient means for causing normal engagement of the lever-sectors with the cable to prevent movements of the gripping-members longitudinally thereof, a second pair of opposed lever-sectors between and eccentrically mounted on said plates, links arranged in pairs and pivotally connected with said lever-sectors, a plurality of cross-bars, each having a pivotal connection with the links of a pair, means for moving the links against the action of said resilient means for releasing the lever-sectors from the cable, a pair of actuating-arms having pivotal connections 25 with the first gripping-member and with said actuating-arms for moving one of said gripping-members longitudinally of the cable after the lever-sectors thereof have been released, and means to adjust the pivotal connection of said actuating-arms longitudinally of the operating-lever.

8. In means for hoisting scaffolds upon cables, a gripping-member connected with the scaffold, a second gripping-member, each of said gripping-members consisting of a pair of opposed, connected plates, lever-sectors arranged in pairs between and eccentrically mounted upon the plates, resilient means for causing normal engagement of the lever-sectors with the cable, members arranged to have upward swinging movements for disengaging the lever-sectors from the cable, and an operating-lever disposed between and connected with said gripping-

members, said lever being movable for increasing or decreasing the distance between the gripping-members.

9. In means for hoisting scaffolds upon cables, a gripping-member connected with the scaffold, a second gripping-member, each of said gripping-members consisting of a pair of opposed, connected plates, lever-sectors arranged in pairs between and eccentrically mounted upon the plates, resilient means for causing normal engagement of the lever-sectors with the cable, links pivotally connected with the lever-sectors, hand-levers arranged to have upward swinging movements to actuate the links for disengaging the lever-sectors from the cable, and an operating-lever having connections with said gripping-members and being movable for increasing or decreasing the distance between said gripping-members.

10. In means for hoisting scaffolds upon cables, a gripping-member connected with the scaffold, a second gripping-member, each of said gripping-members consisting of a pair of connected plates upon opposed sides of the cable, lever-sectors arranged in pairs between and eccentrically mounted on the plates, links pivotally mounted on the sector-levers, springs for normally causing engagement of the sector-levers with the cable, means for causing co-incident movements of the links for disengaging the lever sectors from the cable, and means for increasing or decreasing the distance between the first named gripping-member and second gripping-member while the lever-sectors of one gripping-member are in engagement with the cable.

In testimony whereof, I have affixed my signature in presence of two witnesses.

JASPER E. GOODWILL.
